UNITED STATES PATENT OFFICE.

ROBERT J. SMITH, OF ERIE, PENNSYLVANIA, ASSIGNOR TO CONTINENTAL RUBBER WORKS, OF ERIE, PENNSYLVANIA, A CORPORATION OF PENNSYLVANIA.

DESIGN FOR A TIRE.

59,526.

Specification for Design.

Patented Oct. 25, 1921.

Application filed June 1, 1921. Serial No. 474,262. Term of patent 7 years.

To all whom it may concern:

Be it known that I, ROBERT J. SMITH, a citizen of the United States, residing at Erie, in the county of Erie and State of Pennsylvania, have invented a new, original, and ornamental Design for a Tire, of which the following is a specification, reference being had to the accompanying drawing, forming part thereof.

Figure 1 shows a plan view of a fragment of the tire.

Fig. 2 a section of the tire on the line 2—2 in Fig. 1.

I claim:

The ornamental design for a tire, as shown.

ROBERT J. SMITH.
